United States Patent Office

Des. 177,727
Patented May 22, 1956

177,727

ADVERTISING DISPLAY DEVICE

Jon W. Hauser, St. Charles, Ill., assignor to Hawley Products Company, St. Charles, Ill., a corporation of Delaware

Application February 16, 1955, Serial No. 34,531

Term of patent 14 years

(Cl. D1—2)

FIG. 1

FIG. 2

Fig. 1 is a front perspective view of an advertising display device showing my new design; and

Fig. 2 is a side view of my device.

The panel portion and the border portion of the design are of contrasting colors.

The broken lines shown in Figure 1 are for illustrative purposes only.

I claim:

The ornamental design for an advertising display device, substantially as shown and described.
